UNITED STATES PATENT OFFICE

154,581

DESIGN FOR AN EMBROIDERED EDGING

Alan Badish, Brooklyn, N. Y.

Application September 21, 1948, Serial No. 148,680

Term of patent 7 years

(Cl. D92--1)

To all whom it may concern:

Be it known that I, Alan Badish, a citizen of the United States of America, residing at Brooklyn, Kings County, and State of New York, have invented a new, original, and ornamental Design for an Embroidered Edging, of which the following is a specification, reference being had to the accompanying drawing, forming part thereof.

In the drawing the figure is a plan view of an embroidered edging, showing my new design.

I claim:

The ornamental design for an embroidered edging, as shown.

ALAN BADISH.
